UNITED STATES PATENT OFFICE.

JOHN W. DREISBACH, OF GOLCONDA, ILLINOIS.

AIR SEPARATOR.

Application filed September 22, 1927. Serial No. 221,384.

This invention relates to certain new and useful improvements in air separators for coal, limestone and other materials, the peculiarities of which will be hereinafter described and claimed.

The main objects of my invention are to provide means for intermittently sealing the outlet of the deposited tails from a chamber subject to air suction, thereby increasing the 10 vacuum therein temporarily; secondly, means to facilitate the separation of the finer from the coarser particles by whirling mechanical impact imparting a higher cyclonic velocity to the heavier than to the finer particles; 15 thirdly, to change their direction and drive them out of the normal path of the air currents carrying the finer particles; and fourthly, means to seal temporarily the outlets of coarse and medium tails respectively. 20 In the accompanying drawings on which like reference numerals indicate corresponding parts, Fig. 1 represents a central vertical section of a separator exemplifying my invention; Fig. 2, a horizontal plan view on the line 2—2 of Fig. 1; Fig. 3, a detail end view of a lifting blade, a scraper and mounting; 25 and Fig. 4, a horizontal plan view on the line 4—4 of Fig. 1.

The pulverized coal or other material to be separated is fed through a feeding valve 30 and spout 6 delivering near the center of the top 7 of a closed cylindrical casing 8 in which is centrally mounted a vertical shaft 9, rotated at suitable speed (such as 100 R. P. M.) by bevels 11 and 12, or otherwise from a source 35 of power. A horizontal rotary disc 13 about four-fifths the area of the top, is keyed to said shaft below the top of the casing and forms a rotary table to receive and spread 40 outward over its periphery the feed from said spout. Directly below this table is located a closed drum 14 of approximately the same diameter as the table and about one-fourth the height of the casing, and supported 45 by cross bars 15, or otherwise, so it is fixed. An annular space 16 forming an expansion 50 passage is thus left between the drum and casing for the passage downward of the feed after it leaves the table. Depending from the bottom 55 of said drum is a two-part cylindrical apron 17 having its lower section 18 slidably adjustable on the upper section, preferably by wires over pulleys 19, operated by cranks 20 with ratchet and pawl connections. This 60 apron leaves a wider annular space 21 (about one-third wider) than the annular space 16

above, to allow further expansion and separation of the feed particles as they fall.

Within said depending apron is located a tub-like chamber having cylindrical sides 22, 60 preferably beveled inward at the lower corner 23 where they meet the bottom 24, supported by cross bars 25 or otherwise. An annular passage space 26 of about the same width as the space 21 is thus formed inside the said 65 apron and of about the same depth. A collar 27 of the same diameter as the tub 22, depends from the drum 14, and of a length about the width of the space 16. Between its lower edge 28 and the upper edge 29 of the tub is a 70 space about half the depth of the collar 27, through which the feed particles that are medium and finer, are drawn into the tub chamber after passing upward in the annular space 26, under air suction produced by an exhaust 75 fan or other means (not shown), connected to a pipe 30 passing through the sides of the casing and drum, and having a downwardly extending elbow 31, centrally enclosing the shaft, and provided with a telescoping sleeve 80 32 on its lower end, adjustable by wires over a rod 33, preferably operated by a crank 34 controlled by pawl and ratchet 35 outside the casing.

The collar 27 deflects downward again, the 85 coarser than medium particles that may be drawn upward in the space 26. The bottom 24 of the tub chamber is about opposite the lowest probable adjustment of the lower edge 90 36 of the circular apron dividing the annular spaces 21 and 26. The bottom 24 has an outlet 37 for the medium tails deposited in the tub chamber as will now be described.

A rotary disc 38, located inside the tub chamber near the bottom, is keyed to the central shaft 9, and extends outward nearly to the sides of the chamber so as to leave a small space 39 (about $1/4$ " according to the materials) between its periphery and the preferably beveled sides of said chamber like a false bottom. Discharging scrapers 60, substantially radially mounted, are provided on the underside of said disc and travelling just above the bottom 24, to discharge the medium tails through said outlet 37. The separation 95 of the medium from the finer particles in the stream entering the tub chamber over the upper edge 29, is assisted by a rotary device consisting of forwardly inclined blades 40, acting in a plane between the tub edge 29 and the fines outlet pipe 32, and thus in the path of the 100 annular stream converging at the fines outlet. 105

The outer ends of these blades are preferably connected by a band 41, forming a vertical deflecting wall. The blades and band are supported by posts 42 from the disc 38 or otherwise, so as to rotate with the disc and shaft. These blades strike the particles and by the impact, drive them downward and outward with whirling cyclonic force that affects the heavier particles more than the lighter finer particles, and drives the former whirling against the inside wall of the chamber and downward to the top and periphery of the disc 38, through the annular space 39 into the path of the scrapers 60. The finer lighter particles having less mass, are less affected by the impact of said blades, and are whirled into the vortex and drawn out the pipe 30.

Near the bottom of the casing below the tub chamber, is another rotary disc 43, preferably of about the diameter of said chamber, and keyed to the shaft. On its upper face are mounted a set of blades 52 inclined backward about 45° (Fig. 3) and travelling below the tails outlet 37, and adapted by impact to throw the tails upward and outward past the beveled corner 23 of the tub chamber, and upward in the annular space 26. At the periphery of this disc is a space 44 (similar to 39) between a circumscribing vertical wall 45 and said periphery, through which space the tails pass below and are discharged by substantially radial scrapers 46 into an outlet pipe 47. In said wall 45 above the disc 43, are a series of openings 48 communicating with a circular pipe chamber 49 supplied with return air by the pipe connection 50 (Fig. 2) to the blast side of an exhaust fan or elsewhere. At the forward edge of each air inlet 48 is a wing wall 51 inclined towards the encircling stream of air and of increasing length around the pipe chamber, to deflect proportionate quantities of the air current through the adjacent openings 48. The air currents through the said openings 48 assist in cleaning the tails driven upward by the said blades 52 past said openings. This encircling return air chamber may be dispensed with, if desired. A shelf 53 projecting from the inner wall of the casing, is formed by the top of the air chamber or otherwise, extending below the adjustable apron 18, and above the said encircling wall 45. On this shelf are deposited the primary tails from the annular space 21, as indicated, from which they flow past the air currents from the openings 48 and upon the said rotary disc 43.

Now the operation of this separator is as follows: The pulverized material from the valvular feeder enters the top of the casing near the center of the revolving table and is spread outward in a thin stream as it flows over the edge and downward in the annular expanding passages 16 and 21. The coarsest heaviest particles lodge on the shelf 53 or flow off, while the medium and finer particles

pass under the lower edge of apron 18, upward in the annular space 26, over the top edge 29 of the tub chamber, then arching downward in said chamber they meet the whirling blades 40 inside the vertical band 41. The medium particles are thrown outward and downward to the rotary disc 38, while the fines are drawn out of the vortex through the central adjustable pipe 32, which is lowered to obtain coarser product through the pipe 30, and raised to obtain finer product. As the medium tails collect above and below the periphery of the disc 38, the space 39 is temporarily sealed, but the scrapers alternately discharge the accumulated tails through the outlet 37, whereupon these medium particles (together with the primary tails from the shelf 53), fall upon the disc 43 and seal temporarily the space 44 till the scrapers 46 discharge the accumulation to the outlet 47. This intermittent sealing action at the discs increases the vacuum for the moment and causes a pulsating, throbbing action of the air currents carrying the particles, which assists in separation of the tails. In actual operation of my separator, the tails flow from the spout 47 in a continuous stream at the beginning of operation, but as the feed increases, the discharge of the tails is bunched in rapidly occurring sequence, due to the intermittent sealing action above described.

It will be noted that the annular expanding spaces 16 and 21 are practically dead air spaces, and facilitate the primary separation of the pulverized feed as it descends to the bottom edge of the apron, and is then drawn upward in the space 26 and into the tub chamber for further separation of medium particles.

I have recently demonstrated by actual commercial operation of my separator that I can obtain various grades of finished product as desired, by appropriate adjustment of the parts as above described.

I claim:—

1. A separator comprising a casing, subject to air suction, a vertical rotary shaft centrally mounted therein, walls forming an interior tub chamber with annular side inlet near the top and having a bottom tails outlet, a rotary disc mounted on the shaft over said tails outlet and provided with scrapers below and forming a false bottom adapted to be sealed by tails at its periphery, an exhaust pipe depending in said chamber for fines outlet, and rotary impact fan blades inclined forward and mounted in the path of the material from the side inlet to the fines outlet.

2. A separator comprising a cylindrical casing subject to air suction, a vertical rotary shaft centrally mounted therein, walls forming an interior tub chamber with annular side inlet near the top and having a tails outlet in the bottom, a rotary disc provided with

scrapers below over said tails outlet mounted on said shaft and forming a false bottom in said chamber, an exhaust pipe communicating outside and depending in said chamber 5 for fines outlet, rotary impact fan blades inclined forward and mounted in the path of the material from the side inlet to the exhaust outlet and having a band on their outer ends forming a vertical deflecting wall, substantially as described.

3. A separator comprising a cylindrical casing subject to air suction, a vertical rotary shaft centrally mounted therein, walls forming an interior tub chamber with annular side inlet near the top and having a bottom tails outlet, a rotary disc having scrapers below over said tails outlet mounted on said shaft and forming a false bottom in said chamber, an exhaust pipe to the outside provided with an adjustable sleeve centrally depending in said chamber for fines outlet, rotary impact blades inclined forward and mounted in the path from the side inlet to the exhaust pipe and provided with an encircling deflecting band on their outer ends, and supporting posts from said disc, substantially as described.

4. A separator comprising a cylindrical casing subject to air suction, a vertical rotary shaft centrally mounted therein, walls forming a central tub chamber with annular side inlet near the top and having its lower corner beveled and a tails outlet in the bottom, rotary deflecting and scraping devices mounted in said chamber, a rotary disc mounted on said shaft below said chamber having blades inclined backward for lifting the tails from said chamber past the said beveled corner and provided with scrapers below traveling over a tails outlet in the casing, and an encircling vertical wall at the periphery of said disc, substantially as described.

5. A separator comprising a cylindrical casing subject to air suction having a top inlet near the center, a vertical rotary shaft centrally mounted therein, a rotary feed table in the top of said casing, a closed drum below said table forming with said casing an annular expansion passage, an exhaust pipe located in said drum passing out through the

drum and casing and having a vertical elbow depending below said drum provided with an adjustable sleeve, walls forming a central tub chamber having an annular side inlet near the top below said drum and communicating with said exhaust pipe and having a tails outlet in the bottom, a rotary false bottom with scrapers in said chamber, a mechanical cyclone device rotatably mounted in said chamber, and an adjustable circular apron 60 depending from the bottom of said drum and located between the casing and the side walls of said chamber.

6. A separator comprising a cylindrical casing subject to air suction having a feed 65 inlet near the center, a vertical rotary shaft centrally mounted in said casing, a rotary table below said inlet mounted on said shaft, a closed drum below said table forming with said casing an annular vertical expansion 70 passage, a depending circular apron below said drum but of lesser diameter forming with the casing a larger annular vertical expansion passage and provided with a telescoping end section, a shelf projecting inward 75 from said casing below said apron, walls forming an interior tub chamber located below said drum, an exhaust pipe outside the casing communicating with said chamber, and rotary discs mounted on the shaft with 80 deflecting blades above and scrapers below located in said chamber and below said chamber respectively, substantially as and for the purpose described.

7. A separator comprising a cylindrical 85 casing subject to air suction, a vertical rotary shaft centrally mounted therein, a rotary feed table mounted on the shaft near the top of the casing, walls forming a central tub chamber, deflecting rotary devices mounted on said 90 shaft in said chamber, a rotary disc provided with scrapers and mounted on the shaft near the bottom of said casing, a circular return air pipe in the bottom of said casing forming an encircling wall at the periphery of said 95 disc with air openings above the disc, substantially as described.

In testimony whereof I have affixed my signature.

JOHN W. DREISBACH.
